UNITED STATES PATENT OFFICE.

CHARLES GLOVER, OF NEW BRITAIN, CONNECTICUT.

DESIGN FOR A BICYCLE-PEDAL.

SPECIFICATION forming part of Design No. 29,830, dated December 20, 1898.

Application filed November 28, 1898. Serial No. 697,724. Term of patent 7 years.

To all whom it may concern:

Be it known that I, CHARLES GLOVER, a citizen of the United States, residing at New Britain, county of Hartford, State of Connecticut, have invented and produced a certain new and original Design for a Bicycle-Pedal, of which the following is a full, clear, and exact description.

My invention relates to a new and original design for a bicycle-pedal, and the same is illustrated in the accompanying drawings, in which—

Figure 1 is a perspective view, and Fig. 2 is a plan view.

The leading feature of my design consists, in brief, of what appears to be a substantially solid portion and a skeleton portion, one edge of the part having the solid appearance and one end of the part having the skeleton appearance, meeting at an angle.

A is a substantially solid portion, which in general is of a circular outline. The regularity of this outline is broken, as at B B. At substantially the center of the portion A appears an opening the axis of which is sub-

stantially perpendicular to the plane in which the solid part A appears to be placed.

C is a skeleton portion, one end of which skeleton portion appears to be joined to the edge of the portion A near the offsets B B, so that the skeleton portion C appears generally to be in a plane to one side of yet substantially parallel with the imaginary axial line before mentioned. Viewed in plan, as in Fig. 2, the skeleton portion appears to comprise parallel sides united at their ends and at an intermediate point.

It is the general effect of the pedal as a whole that is the new and original feature and not the appearance of isolated details thereof.

What I claim is—

The design for a bicycle-pedal substantially as herein shown and described.

Signed at New Britain, Connecticut, this 18th day of November, 1898.

CHARLES GLOVER.
